THERMAL DECOMPOSITION OF URANIUM COMPOUNDS

Theodore T. Magel, Cambridge, Mass., and Leo Brewer, Berkeley, Calif., assignors to the United States of America as represented by the United States Atomic Energy Commission

Application March 25, 1947, Serial No. 737,152

7 Claims. (Cl. 75—84)

This invention relates to a method and apparatus for preparing metals, and particularly to a novel method of preparation of high-purity uranium, plutonium, neptunium, and other metals by thermal decomposition of the respective metal halides in a static system or in a dynamic flow system.

The prior hot-filament method of producing pure metals consists broadly of volatilizing a metal compound, such as a metal halide, in the presence of a wire filament which is maintained at a temperature above the decomposition temperature of the metal halide whereby the metal halide is thermally decomposed and the metal is deposited on the hot surface. This prior system is limited to small yields and has not been found satisfactory for producing massive spectroscopic pure metals having an atomic number of 90 or greater. Metals of high atomic number are highly reactive at the higher temperatures, especially above their melting points, and will readily alloy with the hot filament and the associated metallic structure.

Hence, broadly an object of the present invention is to produce a metal, particularly uranium, of extremely high purity in massive form by thermal decomposition of a volatile halide of the metal at a temperature substantially above the decomposition temperature of the metal halide.

Another object of the invention is to provide a novel static hot-surface decomposition method wherein a reducing gas is employed and an apparatus in which the heated surface may be operated at a temperature substantially above the thermal decomposition temperature of the particular metal halide and preferably above the melting point of the particular metal, and the heated surface is substantially unreactive with the metal formed at temperatures above the thermal decomposition temperature of the metal halide.

Another object is a method to produce metal of extremely high spectroscopic purity from a source or mass of the impure metal by a novel continuous-flow hot-filament method whereby a reducing gas is employed and also an apparatus in which a heated surface may be operated at a temperature at least above the decomposition temperature of the metal halide and preferably above the melting point of the particular metal being prepared and wherein the heated surface is substantially unreactive with the metal at temperatures above the thermal decomposition temperature of the metal halide.

Another object is to produce metals of extremely high purity from an impure source of the metal by a novel continuous-flow hot-surface method which may be accurately and efficiently controlled.

Other objects and advantages will become apparent from the following description wherein reference is made to the accompanying drawings in which:

Fig. 1 is a diagrammatic side elevation, parts being in section, of an apparatus suitable for practicing the present invention; and

Fig. 2 is a cross section of a modification of the reaction receptacle of the apparatus illustrated in Fig. 1.

2

For the purpose of illustration, there are described herein a static method and a continuous-flow method employing similar apparatus for the preparation of uranium metal of extremely high purity from an impure mass of uranium metal. The broader aspects of the invention and its application to other metals are apparent from the illustrative examples and are covered in the appended claims.

Broadly speaking, the thermal decomposition method comprises volatilizing a metal halide and exposing the halide vapor to a source of heat which may be maintained at a temperature above the decomposition temperature of the metal halide and preferably above the melting point of the particular metal being prepared so that the metal halide decomposes and the metal is precipitated on the heated surface. The temperature of the heated surface may be raised above the melting point of the metal formed so that the metal drips into and is collected in a suitable refractory container which is positioned so that the metal, during its fall, cools below a temperature at which it may react appreciably with the container, and collects in massive form therein.

In application to uranium metal and employing a dynamic flow system, a halogen such as iodine vapor, preferably in the presence of a reducing gas, such as hydrogen, is passed continuously over an impure mass of uranium metal at very low pressure and in the presence of sufficient heat to cause the production of a uranium iodide vapor which immediately is passed over and is decomposed on a refractory surface, such as a thorium-coated tungsten wire or special carbon filament which is heated to a temperature at least above the decomposition temperature of the metal halide and preferably above the melting point of uranium and is substantially unreactive with respect to the uranium at said temperature. The pure uranium metal is precipitated on the refractory or unreactive surface and continuously drips off, falling into a suitable refractory container which is located so that the dripping uranium metal cools sufficiently during its fall to be substantially unreactive with the refractory container when it is received therein. The waste gases are swept out of the system so that equilibrium conditions are momentarily established and subsequently the excess gases are removed, thereby making the operation continuous.

It is desirable to maintain the pressure in the system very low so as to drive the reaction in the direction of decomposition and precipitation of the metal. By supplying optimum and controlled amounts of iodine vapor and hydrogen and maintaining the system at very low pressures, the decomposition reaction will proceed in the direction of metal formation. Of these very low pressures, which are usually less than 1 mm. of mercury, a pressure in the system of about 0.10 to as low as 8×10^{-5} mm. of mercury has proven most satisfactory.

In another application to uranium metal and employing a static system, a quantity of impure metal is placed in the reaction chamber on a quartz cylinder so that the uranium metal is close to the heated surface. The system is subsequently evacuated to a pressure of approximately 10^{-5} mm. of mercury. The furnace area and the refractory filament are gradually then brought up to a temperature of approximately 500° C. for the furnace area and 1350° C. for the heated surface in order to sufficiently degas the refractory filament as well as the reaction chamber. The system pressure at this temperature approximates 5×10^{-5} mm. of mercury; hydrogen gas at a pressure of approximately 5×10^{-2} mm. of mercury is then introduced into the system, and finally iodine vapor is passed over the impure uranium metal at a pressure of about .9 mm. of mercury thereby forming the metal halide. The system is then closed; most of the metal halide is thermally decomposed within a few

hours. The apparatus is then cooled and the high-purity metal is removed from the system.

Referring to Fig. 1, an apparatus which has been found suitable for practicing the above methods as a flow or static method is illustrated; it comprises a furnace 1 in which is installed a reaction chamber or receptacle 2, preferably of quartz, near one end of which is an exhaust tube 3 which leads to a vacuum pump of the mercury diffusion type (not shown). Intermediate between the reaction chamber 2 and the vacuum pump, a stopcock 3a is placed in the exhaust tube 3 which affords a means for closing off the system when employing static batch method. Extending into the opposite end of the reaction chamber 2 is an inlet tube 4 having a restricted orifice 5 for producing a jet, and an extension or support 6 which extends therefrom and is positioned to support a piece or mass of impure uranium metal in alignment with the orifice 5. A filament 7, preferably a wire, is adapted to conduct, and be heated by, electricity, and it is connected to lead wires which extend through the end of chamber 2 that is opposite inlet duct 4. The filament 7 is positioned in alignment with the orifice 5. To facilitate the removal of the filament, its lead wires are mounted in a ground glass stopper capable of a sealed fit with the end of the chamber 2.

The chamber 2 has a dependent well portion 8 arranged to accommodate a refractory receiving container 9 directly beneath the filament 7 and attached to the chamber 2 by a ground quartz joint. The spacing of the receiving container 9 beneath the filament 7 is sufficiently distant to permit molten uranium metal which drips off from the filament to cool sufficiently so as to be substantially unreactive with the receiving container 9.

For supplying controlled amounts of the halogen and the reducing gas into the chamber 2, the inlet 4 is connected by one branch to a receptacle 10 from which a halogen, such as iodine vapor, may be introduced under the control of a stopcock 11, and by a second branch connected to receptacle 12 which contains hydrogen. In preparing a purer uranium, the halogen is introduced into the inlet duct 4 with hydrogen which is preferably in a very pure and dry condition and the flow rate of which is controllable. For obtaining a controlled flow of pure dry hydrogen, said second branch of the tube 4 is connected to the outlet of the receptacle 12 in which is a palladium thimble 13. The receptacle 12 is located within a furnace 14 and its inlet is connected to a drying receptacle 15 into which hydrogen may be introduced from a suitable source; a purifying trap 16, preferably a liquid air trap, may be interposed between the drying receptacle 15 and the receptacle 12. The receptacle 15 contains an agent for drying the hydrogen used. For hydrogen a suitable agent is P_2O_5 . The trap 16 is for removal of other impurities and in the apparatus illustrated is a conventional liquid air trap. Control of the flow of hydrogen is effected by heating and cooling of the palladium thimble in the receptacle 12; additional control may be provided by a suitable stopcock 11a interposed between the receptacle 12 and the conventional T-connection wherein the halogen is introduced into the system.

The halogen shown illustratively may be iodine vapor and is supplied from a mass of iodine crystals in the receptacle 10, the rate of flow of iodine vapor therefrom being controlled by the temperature and shape of the receptacle 10.

The mixture of iodine vapor and hydrogen in controlled amounts is passed through the orifice 5 and impinges as a jet on the mass M of impure uranium metal which is positioned on the support 6. At the point of impingement of the jet onto the metal, the receptacle 2 is maintained at a temperature at which uranium halide vapor is formed as a result of the reaction of the halogen with the uranium metal. A temperature of from 450 to 550° C. is satisfactory for this purpose. The uranium

iodide vapor thus formed, along with any excess hydrogen and iodine vapor, contacts the filament 7 which may be heated to a temperature at least above the decomposition temperature of the uranium halide and preferably above the melting point of the uranium. In order to continuously establish the melting point of uranium metal, the temperature of the filament 7, should be kept at from 1350° C. to about 1500° C. Uranium of a very high degree of purity will form in small globules on the filament 7 as a result of this decomposition; these coalesce into droplets of sufficient size to drip from the filament 7 into the receiving container 9 which is positioned therebeneath so that when the droplets reach the container 9, they have become cooled below a temperature at which the metal would react appreciably with the container 9. Waste gases and decomposition products are withdrawn from the system through the exhaust tube 3 by the high-capacity vacuum pump when utilizing the dynamic flow method.

The batch method employs the same reacting constituents and apparatus as in the flow method, except that the stopcocks 3a, 11, and 11a are closed after the required amount of uranium halide is introduced into the system at a low pressure. The thermal decomposition reaction of the metal halide will proceed at a more rapid rate and will yield a greater percentage of the metal upon the introduction of hydrogen at a low pressure.

Referring to Fig. 2, a reaction chamber 17 is illustrated, this chamber being in all respects the same as chamber 2 except that it is made of Pyrex glass instead of quartz. The use of Pyrex glass instead of the more expensive quartz is made possible by the introduction of a tantalum radiation shield 18 which surrounds the filament in spaced relation thereto and to the walls of the receptacle 17. The shield is provided with apertures 19 so arranged to permit viewing of the filament and to permit the dripping of the metal from the filament into a receiving container 9. The function of the tantalum shield 18 is to prevent aging and deterioration of the glass which would be occasioned by a direct exposure thereof to radiation.

In operation, to provide a continuous flow, the apparatus, which is sealed between the source of hydrogen and the exhaust tube 3, is first flushed with hydrogen and then evacuated. These steps are repeated alternately until the system is thoroughly cleansed and until the furnace and filament have reached the desired temperatures; a satisfactory vacuum is finally established in the chamber 2. The iodine is brought to the desired temperature. The furnace is heated to produce a temperature of 515 to 520° C. in the reaction chamber 2 at the location of the metal M. The filament temperature may be raised to as high as 1350 to 1500° C. and in the case of uranium to 1450° C. A few experiments will be necessary for determining the temperatures in the case of metals other than uranium.

For contact with uranium, because of its high degree of reactivity at elevated temperatures, a refractory material has to be used that is unreactive with the uranium above the melting point of the latter. A filament found satisfactory for use with uranium is a tungsten wire coated with thorium. A Nernst type filament is particularly good.

The present novel methods of producing pure metals in the presence of hydrogen, therefore, have certain definite advantages among which are that it permits operation above the melting point of the metal, employs to an advantage a refractory-coated filament, uses directly the impure metal as a source instead of iodides or other volatile metal compounds that had to be prepared first, permits very accurate control without danger of contamination, and produces a metal of very high purity.

A number of factors can be varied for effecting control of the operation and for rendering it applicable to

metals other than the uranium illustratively described. Among these factors are the temperature of the metal, filament temperature, pressures, rate of halogen flow, rate of reducing gas or hydrogen flow, and also the surface characteristics of the impure metal source.

The temperature in the vaporizing portion of the reaction chamber should be maintained high enough to cause rapid and complete reaction of the iodine vapor and metal to produce metal iodide vapor, but at the same time the temperature should be sufficiently low so as not to cause appreciable decomposition of the iodide. In the case of iodine vapor and uranium, the preferred temperature appears to lie between 450° C. and 550° C. for the vaporizing portion of the chamber, though the metal temperature may be slightly higher.

The temperature in the decomposition portion, in this example the filament, should be high enough to reverse the initial reaction. The higher the filament temperature, the greater the tendency of the hot metal to react with any excess iodine to reform volatile or non-volatile metal iodides which would be swept out of the system in the dynamic method but not in the static method. For uranium, a filament temperature of 1350° C. appears to be about the minimum temperature for an appreciable reaction rate and operation has been successful at as high a temperature as 1500° C.; about 1450° C. is preferred when producing liquid metal. The metal iodide decomposes on the heated surface of the coated filament and the purified uranium metal formed deposits thereon. The deposited uranium metal, in turn, provides a surface on which additional uranium iodide is decomposed. Since the surface area of the metal on the filament increases until the metal in globules formed drip off, the effective decomposition surface varies periodically within certain limits but maintains itself at a rather constant average for any substantial period of operation.

The rate of iodine flow is proportioned to the state of subdivision of the impure uranium source. Assuming that the surface area of the uranium source is constant, the maximum iodine flow is limited only by the amount of iodine vapor that can react with the uranium. Any excess of iodine above this maximum tends to reverse the reaction at or beyond the filament by combining with metal already precipitated on the filament. Obviously, the iodine flow can be adjusted, and it is increased or decreased in a relationship directly proportional to an increase or decrease, respectively, of the surface area of the metal source.

As mentioned, the rate of flow of iodine vapor is readily controlled by the temperature at which the iodine is maintained, the shape of the receptacle 10 in which the iodine crystals are contained, the degree of low pressure in the system, and the amount of other gas, such as hydrogen, which is introduced.

The flow of hydrogen is controlled by the temperature of the palladium thimble 13 through which the hydrogen is passed before it enters tube 4 and by which it is purified. In the particular case, hydrogen will also react with the halogen freed by decomposition of the halide so as to prevent the freed halogen from recombining with the precipitated metal, as in the case of uranium and iodine vapor. Furthermore, the hydrogen may catalyze the formation of uranium iodide at low temperatures by forming uranium hydride or by forming HI which, in turn, reacts with the uranium. Again, the hydrogen tends to drive the high temperature reaction in the direction of metal production by combining with excess iodine vapor originally introduced, or formed as a result of decomposition of uranium iodide. Another effect which appears to result from the introduction of hydrogen along with controlled amounts of iodine vapor into a low pressure system is that the amount of iodine vapor which would tend to reverse the reaction at the filament if in excess amounts can be more nearly maintained at the exact amount required.

It shall be noted that there will be a pseudo equilibrium for the unstable reversible reaction where uranium will react with the halogen vapor, such as iodine, to form the uranium tetraiodide. Also, there are two possible side reactions, namely the formation of hydrogen iodide and the formation of the uranium tri-iodide from uranium tetraiodide by reaction with hydrogen. Since the heat necessary to decompose or reduce the tri-iodide is somewhat less than that needed for the tetraiodide, the presence of hydrogen in the system will tend to produce greater yields and a more efficient end reaction.

The surface of the filament may be a refractory which is substantially unreactive with the particular metal being prepared at the temperatures above the melting point of the metal, preferably a refractory inorganic compound, or a nonmetallic filament, such as a filament of the Nernst type, should be used. Thoria-lanthana- and urania-coated filaments of tungsten have proven satisfactory. The hot surface used may also be made of a substantially unreacting material such as tantalum; and such surface has proven satisfactory. It is desirable that the surface of the filament be of as high a degree of purity as possible.

For other metals, such as plutonium, thorium, cerium, titanium, formed by thermal decomposition of their respective metal halides, it is advantageous to use other types of filaments, such as Nernst-type filaments, which are refractory, with 85 percent thoria and 15 percent yttria, and filaments with no metal at all. The filament temperature which will give appreciable yields of the metal desired without reacting with the metal or alloys thereof determines the type preferred in a particular case; it should be borne in mind that the lower the operating temperatures required, the less is the chance for alloy formation so that uncoated metal filaments are useful for some purposes. The receptacle 9 may be of thoria, cerous sulfide, or even platinum.

In a preferred operation in the case of uranium, iodine vapor and hydrogen, the temperature in the reaction chamber is maintained at 515° C. to 520° C., the filament is maintained at a temperature of about 1450° C., the pressure in the system, in mm. of mercury, is maintained at about 8×10^{-5} when first evacuated, at 0.9 mm. for the iodine vapor and for hydrogen at from 3×10^{-3} to 1; the ratio of hydrogen to iodine vapor should be about 5 to 1.

While the above invention has been described illustratively as applied to uranium, it is applicable to other metals, including tungsten, vanadium, titanium, thorium, halfnium, zirconium, plutonium, neptunium and the rare earths.

The word "filament" is used herein to denote any body or surface which is heated for effecting decomposition of the vaporized volatile compound of the metal, regardless of its shape or size.

In addition to the thoria coating on the tungsten wire, other refractory surfaces may be provided. These include lanthana for tungsten, tantalum nitride for tantalum, and also a properly machined graphite rod is usable; all of these are unreactive with metals at temperatures as high as 1650° C.

For preparing a thoria-coated tungsten filament, a small piece of tungsten wire is spot-welded across the gap between two ordinary pieces of tungsten and then is covered with a thoria-containing slurry either by dipping or by means of a dropper. The slurry coating is dried in air and then the wire is placed in a chamber where it is subjected to a vacuum while the temperature is slowly brought up to 1650° C.; it is maintained at that temperature for a while, the entire procedure requiring from one to two hours. The slurry coating preferably is made as follows: 25 drops of a saturated thorium nitrate solution in water are added to 5 c. c. of a very thick thoria paste and sufficient water is added to give the proper consistency. In some instances, where the exclusion of water is desirable, anhydrous materials, e. g.

amyl or other alcohol, are used as solvents instead of water. The lanthana-coated tungsten filament is prepared in the same manner, except for the ingredients. Lanthana itself is extremely hard to dehydrate but a slurry of anhydrous lanthana in ethyl alcohol provides a coating which is suitable after the baking procedure.

Another filament is one of tantalum coated with tantalum nitride obtained by heating a tantalum wire very rapidly to an extremely high temperature in an atmosphere of nitrogen. None of these filaments thus coated reacts with metals deposited on them even at temperatures as high as 1650° C., but the base metals of the filaments would react.

Ordinary carbon filaments have been found unsatisfactory. However, a filament prepared by machining an ordinary preformed graphite rod to a very small cross section with a portion having a cross section of less than normal was found satisfactory. The filament is then tapered toward the smallest-diameter portion from a short distance on either side thereof. Such a filament has a section of gradually decreasing cross section toward the intersection of the tapers and thus of varying resistance. The heat at any given point along the tapered portion of the filament depends entirely upon the cross section.

What is claimed is:

1. A method of preparing uranium metal of high purity, consisting in contacting impure uranium metal with halogen vapor at a temperature of between 450° and 550° C. whereby uranium halide vapor is formed; contacting said uranium halide vapor, in the presence of hydrogen, with a refractory surface of a temperature above the melting point of uranium whereby said uranium halide is thermally decomposed and molten uranium deposited on said surface, said surface consisting of material non-reactive with molten uranium; collecting the molten uranium dripping from said surface; and maintaining a subatmospheric pressure of below 1 mm. mercury during the entire operation.
2. The method of claim 1 wherein the temperature of the refractory surface is between 1350° and 1550° C.
3. The method of claim 2 wherein the halogen is iodine.

4. The method of claim 3 wherein the impure uranium is contacted with the iodine at about 515 to 520° C. and the temperature of the refractory surface is maintained at about 1450° C.

5. A method of preparing uranium metal of high purity in a reaction system, consisting in evacuating said system to about 8×10^{-5} mm. mercury; contacting in the created vacuum impure uranium with a mixture of hydrogen and iodine at a pressure of from 3×10^{-3} to 1 mm. mercury for the hydrogen and of about 0.9 mm. mercury for the iodine and at a temperature of between 515 and 520° C. whereby uranium iodide vapor is formed, said mixture having a ratio of hydrogen to iodine of about 5:1, contacting said uranium iodide vapor with a refractory surface of a temperature of about 1450° C. whereby said uranium iodide is thermally decomposed and molten uranium is deposited on said surface, said surface consisting of material nonreactive with molten uranium; and collecting the molten uranium dripping from said surface.

6. The method of claim 5 wherein the refractory surface consists of tantalum.

7. The method of claim 5 wherein the refractory surface consists of thoria.
